UNITED STATES PATENT OFFICE

SALIM N. MALLOUK, OF BROOKLYN, NEW YORK

DESIGN FOR AN EMBROIDERED TABLE COVER OR THE LIKE

Application filed June 6, 1929. Serial No. 31,566. Term of patent 7 years.

To all whom it may concern:

Be it known that I, SALIM N. MALLOUK, a citizen of the United States of America, and a resident of the borough of Brooklyn, Kings County, city and State of New York, have invented a new, original, and ornamental Design for Embroidered Table Cover or the like, of which the following description in connection with accompanying drawing is a specification.

The single figure of the drawing is a plan view of one fourth of an embroidered table

cover or the like, showing my new design. The design shown in the representative illustration is repeated in the other three corners.

The irregular outline extending from the detail illustration in the drawing represents a continuation of the border design shown in detail.

I claim as my invention:

The ornamental design for an embroidered table cover or the like as shown and described.

SALIM N. MALLOUK.
